UNITED STATES PATENT OFFICE.

THEODORE F. ZUCKER, OF NEW YORK, N. Y., ASSIGNEE, BY MESNE ASSIGNMENTS,
TO UNIVERSITY PATENTS, INC., OF NEW YORK, OF NEW YORK, N. Y., A CORPORA-
TION OF NEW YORK.

MEANS FOR DETERMINING THE PHYSIOLOGICAL VALUE OF REMEDIAL AND
MEDICAL SUBSTANCES.

No Drawing.

Application filed November 26, 1923. Serial No. 677,183.

To all whom it may concern:

Be it known that I, THEODORE F. ZUCKER, a citizen of the United States, residing at New York city, county of New York, borough of Manhattan, and State of New York, have invented new and useful Improvements in Means for Determining the Physiological Value of Remedial and Medical Substances, of which the following is a full, clear, and exact specification.

My invention relates to means for determining the secretory action of the stomach and refers particularly to a process for the measurement of the result of varying stomach activity.

Without limiting myself to the particular substances and materials mentioned herein, for purposes of clarity of explanation, I will refer particularly to the application of my invention to antirachitic substances.

It is well known that rickets is due largely to an insufficient amount of available calcium salts or phosphoric compounds in the blood, thus depriving the bones of the amount of these salts and compounds necessary for proper bone growth. The lack of calcium or phosphate in the blood is due to the fact that these substances, while abundant in the food, are to too large an extent in an insoluble form such as insoluble calcium phosphate.

It is evident, therefore, that an antirachitic medicine must be one that will convert the calcium salts and phosphoric compounds from a non-available condition to an available condition in either the stomach or intestines, preferably the former, in order that the intestines may have full opportunity to absorb these salts and compounds as they pass therethrough.

Considering cod liver oil in connection with the process of my invention, I find that this substance is antirachitic as well as a general tonic, or body builder, and I have found that both of these types of action can be referred to a single fundamental pharmacological action; namely, that of stimulating

the secretion of gastric juice in the stomach.

The antirachitic power, or strength, of a drug, therefore, is dependent upon its power, 50 or strength, as an acid excitant in the stomach and the necessity and value of a means for the actual, or comparative, determination of the acid secretion stimulating power of such remedies becomes evident. 55

This is particularly true when many so-called vitamins, and similar bodies, are being offered freely to the public as antirachitic drugs, the actual value of which, in many cases, may be seriously questioned.

My invention, therefore, is of the greatest value not only to scientific investigators but also presents a means whereby the consumer may be protected from misleading advertisements and useless and dangerous drugs.

The object of my invention is a process whereby the actual, or comparative, power of a drug with respect to its ability to stimulate the secretion of hydrochloric acid in the stomach may be readily and accurately ascertained.

It is evident that the tests used as a basis for the determinations must be made upon living organisms and, for that reason, I employ rats as having been found to be best 75 suited for the determination of rachitic conditions.

The present employed method for determining whether a drug is, or is not, an antirachitic medicine, is to feed a rat upon rickets-producing diet, this diet being prolonged for a considerable length of time. Experience has shown that the rats must be of a certain definite age, in order that the tests may have any value. The drug under examination is then fed to the rachitic rat and the results determined by X-ray pictures, or microscopic examinations, of bone sections.

The methods thus employed are qualitative, not quantitative, and determine only whether or not the drug is an antirachitic one. They do not produce results from which one may calculate the degree or com-

parative power of the antirachitic properties of the administered drug.

A method for the determination of the antirachitic strength of a drug through its acid stimulating power is the basis of my invention and comprises generally the measurement of the hydrogen ion concentration of the feces of rats fed with alkaline calcium rich diet, or other rickets-producing diet, before and during the administration of the substance to be tested.

Experiments have shown that on certain diets such as indicated herein, the amount of acid produced in the stomach or added with the food is truly reflected in the pH number of the feces.

The following is an example of the method of my invention:

A rat is kept on an alkaline diet rich in calcium, as, for instance, a mixture of 95% flour, 2% salt, 2.9% calcium lactate and 0.1% ferric citrate. I prefer to maintain the rat upon this diet until the feces show a hydrogen ion concentration of about pH-7.4. I then administer the substance to be tested through the mouth daily and after it has been so administered for five days, I again test the feces for its hydrogen ion concentration.

If $\frac{1}{16}$ of 1 c. c. of a good quality of Norwegian cod-liver oil is thus administered, the feces will show a hydrogen ion concentration of about pH-6.1.

It will thus be seen that the cod-liver oil has converted the hydrogen ion concentration of the feces from pH-7.4 to pH-6.1, a conversion from the alkaline side to the acid side, thus demonstrating not only that the administered substance has an acid secretion stimulating power but also clearly expressing the amount of such excitant property in terms which can be employed as a medium for determining and expressing the comparative value of substances, as acid-excitants within the stomach and intestines.

The comparative acid excitant strengths of two substances can be readily and accurately determined by the comparative feeding of two rats with the same food, examining their feces for their hydrogen ion concentration, feeding them comparatively with the substances to be tested and again testing the feces for their hydrogen ion concentration.

It is to be noted that in the previously employed methods of testing antirachitic substances the results are determined by X-ray photographs or by microscopic examinations of bone sections, neither of which results is determinative of the antirachitic power, or strength, of the substance, nor capable of being applied as a means for comparative determinations between a plurality of such substances.

The previously employed methods, there-

fore, determine only whether a substance is, or is not, antirachitic in its results, while the method of my invention determines whether a substance is, or is not, antirachitic and if it is, my method further determines the amount of its antirachitic strength and expresses such amount in definite and understandable terms capable of comparative application and expression.

My method, therefore, presents a means for determinations of the highest scientific and practical value, in that it allows of the accurate determination of the acid excitant power, or strength, of a substance and enables such substance to be readily compared with other substances.

It is evident that by the method of my invention all suspected acid excitants may be accurately and permanently formulated as to their strength and their usefulness for this purpose may be scientifically determined.

I do not limit myself to the particular chemicals, temperatures, proportions, periods of treatment or other conditions, or steps of treatment, mentioned, as these are simply given as a means for the clear explanation of my invention.

What I claim is:—

1. The process of determining the comparative acid secretion excitant strength of a substance which comprises determining the pH value of the feces of an animal, feeding a known quantity of said substance to the animal and determining the pH value of the feces after such feeding.

2. The process of determining the acid secretion excitant strength of a substance which comprises determining and comparing the pH values of the feces of an animal before and after a known quantity of the substance has been administered internally into said animal.

3. The process of determining the acid secretion excitant strength of a substance which comprises internally administering an alkaline substance into an animal, determining the pH value of the feces, internally administering a known quantity of the substance to be tested and determining the pH value of the feces after the administration of said substance to be tested.

4. The process of determining the acid secretion excitant strength of cod-liver oil which comprises internally administering an alkaline substance into an animal, determining the pH value of the feces, internally administering a known quantity of cod-liver oil and determining the pH value of the feces.

5. The process of determining the antirachitic strength of a substance which comprises internally administering a rickets-producing substance into an animal, determining the pH value of the feces, internally

administering a known quantity of the anti-rachitic substance and determining the pH value of the feces.

6. The process of determining the anti-rachitic strength of a substance which comprises internally administering an alkaline rachitic producing substance into an animal, determining the pH value of the feces,

internally administering a known quantity of antirachitic substance and determining the pH value of the feces.

Signed at New York City in the county of New York and State of New York this 23rd day of November, 1923.

THEODORE F. ZUCKER.
